BOTTLE CUTTING APPARATUS

Ben R. Myrick, P.O. Box 595, Grand Coulee, Wash.
99133, and Wayne E. Myrick, Electric City, Wash.
(P.O. Box 1191, Grand Coulee, Wash. 99133)

Filed Feb. 15, 1973, Ser. No. 332,724

Term of patent 14 years

Int. Cl. D8—03

U.S. Cl. D8—98

FIG 1

FIG 2

FIG 3

FIG. 1 is a side elevation view of the bottle cutting apparatus;

FIG. 2 is a side view opposite to FIG. 1;

FIG. 3 is an end view as seen from the right in FIG. 1;
FIG. 4 is an enlarged sectional view taken along line 4—4 in FIG. 1;

FIG. 5 is an enlarged sectional view taken along line 5—5 in FIG. 1;

FIG. 6 is an enlarged sectional view taken along line 6—6 in FIG. 1;

FIG. 7 is an enlarged sectional view taken along 7—7 in FIG. 1;

FIG. 8 is an enlarged fragmentary end view taken along 8—8 in FIG. 1;

FIG. 9 is an enlarged fragmentary end view taken along 9—9 in FIG. 1; and

FIG. 10 is an enlarged fragmentary sectional view to a typical handle cross section as seen along line 10—10 in FIG. 1.

We claim:

The ornamental design for a bottle cutting apparatus, as shown.
